Patented Dec. 19, 1916.

FIG. 1.

FIG. 2.

FIG. 3.

UNITED STATES PATENT OFFICE.

HARRY A. HOKE, OF ALTOONA, PENNSYLVANIA.

ELLIPTICAL SPRING.

1,209,436.

Specification of Letters Patent. Patented Dec. 19, 1916.

Application filed June 3, 1916. Serial No. 101,441.

To all whom it may concern:

Be it known that I, HARRY A. HOKE, a citizen of the United States of America, and a resident of Altoona, in the county of Blair 5 and State of Pennsylvania, have invented a certain new and useful Improvement in Elliptical Springs, of which the following is a true and exact description, reference being had to the accompanying drawings, which 10 form a part thereof.

My present invention relates to elliptical leaf springs composed of a plurality of spring units arranged side by side, such as are commonly used in the trucks of locomotive tenders, and the object of my invention 15 is to provide simple and effective connecting means which will permit a closer spacing of the different units composing each complete spring structure than has been heretofore practically possible and will at the 20 same time insure the desired uniformity in the movement and in the distribution of the load carried by the different units.

The various features of novelty which 25 characterize my invention are pointed out with particularity in the claims annexed to and forming a part of this specification. For a better understanding of the invention, however, and the advantages possessed by 30 it, reference should be had to the accompanying drawings and descriptive matter in which I have illustrated and described a preferred embodiment of my invention.

Of the drawings: Figure 1 is a plan view 35 with parts broken away and in section, of a spring structure embodying my present invention; Fig. 2 is an elevation of the spring structure shown in Fig. 1, with parts broken away and in section; and Fig. 3 is a 40 section taken on the line 3—3 of Fig. 2.

The spring structure shown in the drawings comprises three elliptical spring units proper. Each spring unit consists of an 45 opposing pair of spring sections A, each in the form of a bunch of spring leaves. As shown, the two bunches of spring leaves forming each unit are similar to one another, each comprising leaves A¹, A², A³, A⁴, A⁵, A⁶, A⁷, A⁸ and A⁹. In the preferred 50 construction illustrated the inner leaves A¹ and A² of each spring section are inturned and the different sections are connected together at their opposite ends by recessed end members B and bolts C as in the con-

struction disclosed and claimed in my prior 55 Patent No. 1,101,931 granted June 30, 1914.

The different leaves of each spring section are held together midway between the ends of the section, and are connected to the central portion of the corresponding sections of the other units by an integral connecting member D, formed of wrought metal or cast steel in ordinary practice, and provided with a plurality of open ended 60 passages D' one for each spring unit in 65 which the corresponding bunch of spring leaves of that unit is received. The walls of each passage D' snugly surround the central portion of the bunch of spring leaves passing through it. In consequence the central portions of the different leaves composing each bunch or spring section, are not only firmly held together, but are rigidly 70 connected to the central portions of the corresponding spring sections of the different 75 units.

The connection of the different spring units at their centers by the integral connecting members D gives certain substantial practical advantages over the construction heretofore commonly employed in which the bunch of spring leaves forming each spring section have been connected at their centers by an individual band surrounding the bunch and separate from the 80 bands surrounding the central portions of the other spring sections. For one thing, 85 my improved construction permits the different spring units to be spaced closer together than is possible where individual 90 bands are employed, and in the second place, the use of the present invention insures a more uniform movement of the different 95 spring sections, and a more uniform distribution of the load carried thereby than is had with the individual band construction.

The uniformity of movement and load distribution is obtained not only because of the rigid connection between the central portions of the different spring sections 100 made possible by the use of my improved connecting members D, but is enhanced by the closer spacing of the different units, and by the fact that the closer spacing of the units makes the end connections formed 105 by the recessed members B and bolts C, more effective in their tendency to produce uniform action. With the new construction

the ends of the spring sections may fit snugly between the transverse webs or ears B' of the members B and these webs or ears need not be made any thicker than is desirable to give the necessary strength.

The increase in capacity of the spring received in a given space made possible by the use of the present invention is peculiarly important in the case of springs employed in 10 the trucks of locomotive tenders for which use my present invention was primarily devised. This follows from the fact that on very large tenders it is necessary to use correspondingly large axles and other parts, 15 including springs. An increase in the width of springs to carry the required load increases the wheel base of the truck and, therefore, the wheel base of the tender, not only by the amount of increase in the width 20 of the spring, but also by the amount of space required for the heavier parts incident to the greater span between centers of truck wheels. It is also advisable to put the center pins of the trucks of a tender as far 25 apart as possible as the increase of this distance makes the tender more stable on the truck. If the wheel base of the truck is increased more trouble is found when overcoming interferences with the front and back 30 steps and other parts on the tender frame if the distance between the truck centers is not reduced.

In the practical use of the invention I have been able to provide a locomotive truck 35 spring in accordance with the present invention, which is approximately 17 per cent. stronger than a spring occupying the same space and made with the separate central bands heretofore used.

40 Having now described my invention, what

I claim as new and desire to secure by Letters Patent, is:—

1. A spring structure comprising in combination a plurality of elliptical spring units arranged side by side and each consisting of 45 an opposing pair of bunches of spring leaves, means connecting the different bunches of spring leaves at their opposite ends, and an integral member connecting one spring leaf bunch of each unit with the corresponding 50 bunches of the other units and formed with individual open ended passages for the different bunches connected by said member, each of said passages receiving, and the walls thereof closely surrounding the central portion 55 of the corresponding bunch of spring leaves.

2. A spring structure comprising in combination a plurality of elliptical spring units arranged side by side and each consisting 60 of an opposing pair of bunches of spring leaves, a chambered member at each end of the spring structure for connecting the corresponding ends of the different bunches of spring leaves together, said member being 65 formed with transverse webs interposed between the different units, and a pair of integral members one connecting one spring leaf bunch of each unit with the corresponding bunches of the other units and the other 70 similarly connecting the other spring leaf bunches, each of said integral members being formed with individual open ended passages for the different bunches connected by it, each of said passage receiving, and the 75 walls thereof closely surrounding, the central portion of the corresponding bunch of spring leaves.

HARRY A. HOKE.
